S. H. MUDGE,
FOLDER FOR WINDOW ENVELOP INCLOSURES,
APPLICATION FILED SEPT. 25, 1914.

1,164,844.

Patented Dec. 21, 1915.

UNITED STATES PATENT OFFICE.

SOLOMON H. MUDGE, OF CHICAGO, ILLINOIS.

FOLDER FOR WINDOW-ENVELOP INCLOSURES.

1,164,844.

Specification of Letters Patent. Patented Dec. 21, 1915.

Application filed September 25, 1914. Serial No. 863,444.

To all whom it may concern:

Be it known that I, SOLOMON H. MUDGE, a citizen of the United States, residing at Chicago, in the county of Cook and State 5 of Illinois, have invented a new and useful Improvement in Folders for Window-Envelop Inclosures, of which the following is a specification.

The object of my invention is to facilitate folding telegrams, cablegrams, bills, letters and paper sheets generally, like those specified, bearing addresses, in a manner to register the address with the outlook-section of an envelop of the "window" type 15 receiving such an inclosure.

I have more especially devised my invention, for accomplishing by its use the aforesaid purpose, for folding telegrams (including cablegrams); and while not intending 20 to limit it to such particular use, it is hereinafter described in that connection with reference to the accompanying drawing, in which—

Figure 1 is a perspective view of the 25 folder shown fastened to a stable support; Fig. 2 is a face view of the same with a telegram in position to be folded; Fig. 3 is a view in elevation of a window-envelop shown in position to be applied over the 30 folded telegram on the mandrel or plate of the folder, and Fig. 4 is a section on line 4, Fig. 2, showing the telegram in its folded condition.

The preferred embodiment of my invention 35 is that most clearly illustrated in Figs. 1 and 2, involving the following described construction: A flat plate 5, which may be formed of brass or any other suitable metal or adequately stiff material, approximates 40 in shape that of an envelop to be used for inclosing a telegram 6 when folded. The lateral and upper edges are preferably chamfered on both sides of the plate, as represented of the lateral edges in Fig. 4, and a recess 7 is shown to be provided centrally in the upper edge. The plate should taper slightly toward the upper end, as shown, for a purpose hereinafter explained. To the face of the plate is fastened, through 45 50 a spacing member 8 on its lower end, a supporting base comprising a flat leg 9, which may be of the same material as the plate, and which inclines upwardly and back-

wardly from a foot 10, when the latter is fastened, as shown, to a stable support 11, 55 such as a table, ledge, desk, or the like. The upper reduced section of the leg 9 contains an elongated slot 12 to correspond in its position to that occupied by the slot 12^a provided in a so-called window envelop 13 60 (Fig. 3), and which is usually covered with waxed paper or other transparent material, though that is not essential to the use of my invention. In the lower end of the plate 5 is shown an elongated horizontal slot 14, 65 extending entirely through the plate and in which is confined water-absorbent material 15, such as sponge or felt, for the purpose hereinafter explained.

To use the device, a telegram 6 is applied 70 to the front face of the plate by inserting it edgewise into the space between the latter and the looped section of the leg until the lower edge of the sheet meets the straight edge of the spacer 8 for truing the sheet in 75 position, the adjustment of the sheet being such as to register the address at 16 upon it with the loop 12. Upon then folding the lateral edges of the telegram backwardly at the rear face of the plate or mandrel 5 into 80 the condition represented in Fig. 4, and then folding backwardly, over the upper edge of the same, the section which extends beyond its upper end, the folded sheet will 85 fit into an envelop and the address upon it will register with and be exposed at the envelop-slot 12^a. The chamfered edges of the mandrel serve to sharpen adequately the creases of folding, but unless the plate be made to taper along its lateral edges, as described, or other preventing means be provided, the inwardly folded flaps on the section of the sheet which is turned backwardly 90 over the upper end of the plate, tend to spread outwardly, thereby not only rendering the folded sheet untidy in appearance, but augmenting the width to an extent that interferes with ready insertion into the envelop. These tapering edges of the mandrel 95 overcome that tendency by slightly widening the flaps and thus narrowing the folded sheet toward the upper end of the latter in performing the first-described folding operation.

Preparatory to inserting the folded sheet 105 into its envelop, it may be gripped at the re-

cess 7 and withdrawn from the mandrel; or if the envelop used be, like that represented in Fig. 3, of the variety having an open insertion-end provided with a cemented 5 coated flap 13^a, it may, before withdrawing the folded sheet, be slipped endwise over the latter while on the mandrel, and withdrawn therefrom, at the recess 7, with the telegram inside. In the last-named in-

stance the coated part of the flap 13^a brushes over the wet sponge 15 to be moistened and rendered adhesive for sealing the envelop.

Whether the inclosure be a telegram or other addressed sheet, the use of my device 15 for properly folding it to register the address with the envelop-window renders the operation expeditious and thus time-saving, and tends to prevent mistakes. These advantages may be best explained in the case 20 of telegrams: The messages which are taken on a telegraph blank and usually written on a typewriting machine, can not, without great loss of time and the exercise of considerable skill on the part of the machine-operator, be so disposed on the blank as to bring the address in proper position to register with the envelop-window. Therefore, it is the usual practice to typewrite the messages on the blanks without reference to any 25 positioning of the addresses, and send the telegrams to clerks in another department for insertion into and sealing the ordinary type of envelopes, on which the clerks laboriously copy the addresses in long hand, with the result that mistakes occur in copying, 30 entailing delay in the delivery of messages, besides that caused by thus addressing the envelopes and the cost of the additional labor. Furthermore, the provision of the moistening pad or medium 15 saves the need of wetting the envelop-flap as a separate operation and thus economizes in time and labor.

As will be understood from the foregoing description, the gist of my invention lies in 45 providing a plate or mandrel for folding an addressed sheet of paper, with means for so registering the address on the mandrel as to cause the address on the folded sheet to register with the outlook-opening in a window-envelop when inclosed in the latter. The looped section of the leg 9 affords the best means now known to me for the purpose, but any of various other means for indicating on the mandrel the position for the 50 sheet to adapt it, by folding, to so register the address when the sheet is inclosed in a window-envelop, will serve the same purpose; and all such means are intended to be included in my invention.

60 What I claim as new and desire to secure by Letters Patent is:

1. As an article of manufacture, a folding device for address-bearing window-envelop inclosed sheets, comprising a supporting base-member, a plate carried thereby and

projecting therefrom and adapted to have a sheet manually folded about it, and means with which to register the address on the sheet, in folding the latter, to coincide with the window in such an envelop when the 70 folded sheet is inclosed therein.

2. As an article of manufacture, a folding device for address-bearing window-envelop inclosed sheets, comprising a base-member, a plate supported thereby and projecting 75 therefrom and having its edges beveled on both sides and adapted to have such a sheet manually folded about it, and provided with means with which to register the address on the sheet, in folding the latter, and to coincide with the window in such an envelop 80 when the folded sheet is inclosed therein.

3. As an article of manufacture, a folding device for address-bearing window-envelop inclosed sheets, comprising a supporting 85 base, a plate carried thereby and projecting outwardly therefrom, said plate tapering along its lateral edges toward one end and having its edges beveled and adapted to have such a sheet manually folded about it, 90 and means on and spaced from the face of the plate with which to register the address on a sheet, in folding the latter, to coincide with the window in such an envelop when the folded sheet is inclosed therein.

4. In a folding device for address-bearing window-envelop inclosed sheets, a stationarily supported plate adapted to have such a sheet folded about it, and a loop extending on and spaced from the plate, with which 100 to register the address on the sheet in folding the latter about the plate to coincide with the window in such an envelop when the folded sheet is inclosed therein.

5. In a folding device for address-bearing window-envelop inclosed sheets, a leg adapted to be fastened to a stable support and provided with a loop in one end, and a plate secured near its lower end to and spaced from the leg to extend the loop along the 105 face of the plate.

6. In a folding device for address-bearing window-envelop inclosed sheets, a leg adapted to be fastened to a stable support and provided with a loop in one end, a plate secured 110 near its lower end to the leg to extend the loop along the face of the plate, and a spacer forming a sheet-stop interposed between the plate and leg.

7. A folding device for address-bearing window-envelop inclosed sheets, comprising a leg provided on one end with a foot for fastening the device to a stable support and provided with a loop in its opposite end, a plate tapering at its lateral edges toward 115 its upper end and secured near its lower end to the leg to extend the loop along the face of the plate, and a spacer forming a sheet-stop interposed between the plate and leg.

8. A folding device for address-bearing 120

window-envelop inclosed sheets, comprising a leg provided on one end with a foot for fastening the device to a stable support and provided with a loop in its opposite end, a plate having beveled edges and a recess in its upper edge and secured near its lower end to the leg to extend the loop along the face of the plate, and a spacer forming a sheet-stop interposed between the plate and leg.
